a corporation of Illinois

Application December 30, 1949, Serial No. 136,001

21. Claims. (Cl. 11—1)

1

This invention relates to improvements in binding machines and more particularly relates to an improved binding machine adapted to spread plastic binding elements for the impaling of sheets to be bound thereon and having a novel form and arrangement of means for feeding the binding elements one by one for spreading; together with an indexing means for indexing the binding elements into position for opening and impaling the sheets to be bound thereon.

Heretofore, in binding books with plastic binding elements having a backbone extending the length of the binding element and spaced rings extending therefrom, the rings of the binding element are usually opened or spread to permit the sheets to be bound to be impaled thereon by means of a spreading device commonly called a binding machine. The spreading device usually has a plurality of upright fingers acting as a holding means for the backbone of the binding element and extending between the rings thereof and engaging the backbone thereof for spreading. The rings are usually spread by means of a plurality of hook-like fingers engageable with the insides of the rings and then movable longitudinally to spread or open the rings while the backbone of the binding element is held by the backbone holding means. The binding machine itself may be operated manually or by power, but due to the light weight of the binding elements it has not been thought practical to make such machines automatic or even semi-automatic. This is on account of the difficulty of feeding the light binding elements one by one so they will fall into the proper position between the fingers of the binding machine. This is particularly true with binding elements of small diameters and short lengths, which very seldom come to rest in the same position. At times the backbone proper of the binding element will come to a stop against the backbone holding means and at times the rings themselves will fall to face the backbone holding means, which is the position desired, and at other times only one edge of the backbone will come to a stop against the holding means, preventing the binding element from indexing itself properly between the fingers of the backbone holding means.

My present invention has as one of its objects to overcome these difficulties by providing a novel and simple form of means for feeding the binding elements one at a time and allowing them to drop against the backbone holding means for the binding element, and by providing a simple form of movable indexing device upon which a binding element drops under control of the operator of

2

the machine, which rotates the binding element against the backbone holding means and moves it into position to set and index itself with the rings thereof between and beyond the backbone holding means and the fingers of the backbone holding means extending between the rings and engaging and holding the inside of the backbone.

Another and principal object of my invention is to provide a novel and simple form of indexing and feeding means for plastic binding elements, arranged to feed and index the binding elements one at a time in a positive and uniform manner into the proper position for opening or spreading.

Another object of my invention is to provide a new and improved semi-automatic binding machine having a novel form of feeding means therefore arranged to feed the binding elements in position for spreading one at a time under control of the operator of the machine.

20 A still further object of my invention is to provide a new and improved form of a semi-automatic binding machine with a novel form of feeding and indexing means automatically and uniformly moving each binding element into position between the backbone holder fingers of the binding machine for spreading or opening to permit the sheets to be bound to be impaled thereon.

25 A still further object of my invention is to provide a novel form of indexing device adapted to uniformly and positively position plastic binding elements into the proper position for opening or spreading for the impaling of the sheets to be bound thereon.

30 These and other objects of my invention will appear from time to time as the following specification proceeds and with reference to accompanying drawings wherein:

Figure 1 is a top plan view of a binding machine having a feeding and indexing means constructed in accordance with my invention embodied

40 therein;

Figure 2 is a fragmentary substantially longitudinal sectional view taken through the binding machine shown in Figure 1;

45 Figure 3 is an enlarged fragmentary elevational view of the machine shown in Figure 1 with certain parts thereof broken away and certain other parts shown in substantially longitudinal section, in order to show certain details of the feeding means for the binding element; and

50 Figure 4 is an enlarged fragmentary detail view showing certain details of the indexing means for the binding elements not shown in Figures 1 and 2.

As shown on the drawings:

A binding machine 10 is shown in Figures 1 and 2 as comprising a casing 11 having an inclined table 12 at the forward end thereof on which the sheets to be bound are placed for impaling on the upright ends 13-13 of the spread rings 14-14 of a binding element 15.

The binding elements 15-15 may be made from sheets of thermo-plastic material, preferably of a non-explosive and slow burning type, and as shown in Figures 1 and 2 have a backbone portion 16 extending along the outside of the bound volume at the back thereof, with the spread rings 14-14 extending therefrom.

The binding machine 10 has a plurality of laterally spaced fingers 19-19 extending upwardly from the table 12 and adapted to engage the backbone 16 of the binding element between the rings 14-14 thereof and to hold the backbone in an upright position, so the rings may be uncured or spread with the ends 13-13 extending upwardly from the table 12, to receive the sheets of paper to be bound. When the backbone holding fingers 19-19 are in engagement with the backbone of the binding element, with the rings thereof extending forwardly of said fingers, the backbone holding fingers are moved transversely of the table 12 to move the rings 14-14 into engagement with the transversely extending ends of spreading fingers 20-20. The spreading fingers are movable longitudinally of the table, to uncurl or open the rings, with the backbone thereof held in an upright position by the backbone holding fingers 19-19.

The binding machine 10 may be of any well known form and is herein shown as being of a type somewhat similar to that shown and described in a prior application Serial No. 773,578, filed by me on March 10, 1947, so is only herein shown and described insofar as is necessary to make my present invention readily understandable. A backbone holding element 21 from which the upright fingers 19-19 extend is herein shown as extending upwardly from and being mounted on a transversely movable bar 22 suitably guided beneath the top of the table 12 for transverse movement with respect thereto. The bar 22 and fingers 19-19 are moved transversely of the table 12 to position the rings for engagement with the transversely extending ends of the spreading fingers 20-20 by means of a spring (not shown) acting against a cam 23 formed on one face of a sector 24. The sector 24 is freely mounted on a transverse shaft 25 suitably journaled in opposite side walls 26-26 of the casing 11.

The spreading fingers 20-20 may be mounted on and project angularly upwardly and rearwardly from a longitudinally movable member 27 slidably guided on laterally spaced transverse shafts 28-28 spaced beneath the top of the table 12 and extending longitudinally thereof in parallel relation with respect thereto. A link 29 is pivoted to the sector 24 at one of its ends and has a slot 30 at its opposite end, engaging a pin or bolt 31 extending from a lug 31, depending from the member 27. The slot 30 in the link 29 is provided to delay longitudinal movement of the spreading fingers 20-20 until the cam 23 has moved into position to allow the backbone holding fingers 19-19 to move laterally and move the binding element into position to come into engagement with the transversely extending ends of said spreading fingers. Another link 33 pivoted to the sector 24 is pro-

vided to move said sector about the axis of the shaft 25. Said link may be operated by a suitable system of levers (not shown), either operated manually or by power. Said operating means is not herein shown or described since it is not part of my present invention.

Spaced above and rearwardly of the table 12 and extending in the same angular direction as said table is a feeding plate 34 along which the binding elements are adapted to move and drop therefrom one at a time into position to engage the fingers 19-19 and index themselves therebetween for spreading. The feeding plate 34 is mounted on the top of the casing 11, or may be a part thereof, and is shown as having a blank receiving hopper 35 extending across its upper or receiving end and forming a magazine feeder for the binding elements 15-15. The hopper 35 has a rear wall 36 herein shown as extending vertically of the feeding plate 34 and a front wall 37 extending parallel thereto with its lower end spaced above said feeding plate to allow the bonding elements to pass thereby. The front wall 37, as herein shown, has a plate 38 mounted thereon for vertical adjustment with respect thereto, in accordance with the diameter of the binding elements being spread, to allow one row of binding elements only to move downwardly along the feeding plate 34. The plate 38 is held in its various desired positions of adjustment by bolts and wing nuts indicated generally by reference characters 40-40 and extending through vertical slots 41-41 in the wall 37. The blank receiving hopper 34 also has one fixed side wall 42 with a side guide plate 43 extending forwardly therefrom, forwardly of said hopper, to form a guide for one side of the binding element. It also has an opposite side wall 44 slidably mounted between the rear and front walls of said hopper for adjustable movement therewith to take care of various lengths of binding elements. The wall 44 is adjustable along slots 45-45 extending along the front and rear wall 37 and 36 and is held in fixed relation with respect thereto on bolts and wing nuts indicated by reference characters 46-46. A side guide plate 53 is shown as extending forwardly of the adjustable side wall 44, and with the side guide plate 43 forms an adjustable guide for the ends of the binding elements as they leave the hopper 35 and pass downwardly along the feeding plate 34. The side guide plate 53 has a vertical slot 54 formed therein to receive the plate 38 when adjusted for smaller binding elements than those shown in the drawings.

Extending across the forward ends of the guide plates 43 and 53 is a vertically movable bar 55 governing the binding elements 14 leaving the hopper 35, and herein called a stop and go bar for convenience. The stop and go bar 55 has opposite inwardly turned end portions 56-56 extending rearwardly therefrom and depending therefrom from which extend arms 57-57 herein shown as being continuations thereof and extending rearwardly therefrom to a point adjacent the rear end of the casing 11. The arms 57-57 have upwardly extending rear end portions 58-58 pivotally mounted at their upper ends on sleeves 59-59 mounted on a transverse shaft 60. The transverse shaft 60 is mounted at its opposite ends in angularly extending slots 61-61 formed in opposite side walls 26-26 of the casing 11 in parallel relation with respect to the feed plate 34. The slots 61-61 afford a means for adjusting the stop and go bar 55 with respect to a transverse

extending stop and drop bar 65, extending across the forward end of the feeding plate 33, to take care of various diameters of binding elements. The arms 57-57 are freely mounted on opposite ends of the transverse shaft 60 on flanged sleeves 66-66 encircling said shaft and abutting the outer sides of the side walls 26-26. Collars 67-67 mounted on said shaft abut the outer ends of said sleeves to retain the arms 57-57 thereto. The collar 67 on one end of said shaft is retained thereon as by a snap ring 68. The other collar is retained on said shaft by a wing nut 69 threaded on the outer end of said shaft and also serving to hold said shaft and the arms 57-57 in the desired position along the slots 61-61 by clamping the flanged sleeves 66-66 to opposite side walls 26-26. The arms 57-57 and the stop and go bar 55 are held in an upright position to allow the binding elements to pass beneath the bottom of said bar by means of two spaced springs 70-70 seated at their lower ends on supports 71-71 projecting laterally outwardly from opposite side walls 26-26 of the casing 11. The springs 70-70 are seated at their upper ends in retaining lugs depending from the bottoms of the arms 57-57.

A stop bar 73 extends angularly upwardly and rearwardly from the top of the feed plate 34 from a point disposed in advance of the forward end thereof. The bottom of said stop bar is adapted to be engaged by a pin 74 extending outwardly from an inwardly turned end 56 of the stop and go bar to hold the bottom of said bar in the proper position of elevation with respect to the feed table 34 as the shaft 60 is adjustably moved along the slots 61-61. The stop bar 73 is so inclined as to hold the stop and go bar 55 in position to allow a binding element of the required diameter to pass therebeneath in all positions of adjustment thereof with respect to the ends of the plate 34.

The stop and drop bar 65 extending across the forward end of the feed plate 34 has two arms 75-75 extending rearwardly from opposite ends thereof beneath the top of the feed plate 34. The arms 75-75 have upturned rear ends secured to a transverse shaft 76 pivotally mounted on opposite side walls 26-26 of the casing 11.

Compression springs 77-77 are seated at their lower ends on supports 79-79 extending inwardly from side walls 26-26 of the casing 11. Said springs are seated at their upper ends on the bottoms of the arms 75-75 to urge said arms and the stop and drop bar 65 in an upwardly extended position with respect to the feed plate 34 to prevent a binding element from dropping from the discharge end thereof.

An arm 80 is secured to an outer end of the transverse shaft 76 to pivot said shaft and move the stop and drop bar 75 downwardly beneath the top of the plate 34 into position to allow a binding element 15 to drop from the discharge end of said plate. An arm 81 is secured to the opposite end of the shaft 76 from the arm 80. Pins 82 and 82a extend inwardly from the respective arms 80 and 81 for engagement with the arms 57-57, to move the stop and go bar 55 downwardly with the stop and drop bar 65 against the springs 70-70, upon downward movement of said arms. This will stop the next succeeding binding element from moving into position to drop from the end of the feeding plate 34.

Thus, upon downward movement of the stop and drop bar 65 against the springs 77-77 into the position shown in Figure 4, a binding element 15 may roll from the discharge end of the feed

plate 34 against the backbone holding fingers 19-19. At the same time the pins 82 and 82a will engage the arms 57-57 and move the stop and go bar 55 downwardly against the springs 70-70 to block the next succeeding binding element from downward movement along the feed plate 34. Upon release of the hand from the arm 80 the springs 77-77 will move the stop and drop bar 65 upwardly into the position shown in Figure 2. The springs 70-70 will also move the stop and go bar upwardly into position to allow a binding element 15 to move downwardly along the feed plate 34 into engagement with the stop and drop bar 65.

One binding element at a time may thus be fed from the end of the feeding plate 34 to the backbone holding fingers 19, and when larger or smaller binding elements are being used, adjustment of the stop and go bar 55 along the slots 61-61 may be attained by loosening the wing nut 69 on the shaft 60 and moving said stop and go bar to a position where the space between the bars 55 and 65 is substantially equal to the diameter of the ring being spread. At this time the bar 73 will lower the stop and go bar 55 or permit it to raise in accordance with the diameters of the rings being spread.

The means for rotating the binding element 15 into position for its rings to come between the backbone fingers 19-19 and its backbone to come into engagement with said fingers, as shown by dotted lines in Figure 3, includes a power driven indexing roll 83 journaled adjacent its opposite ends on the upper ends of two laterally spaced links or lever arms 84-84 and herein shown as being secured at their lower ends to the transverse shaft 25 and affording a means for adjusting the position of the roller 83 with respect to the backbone holding fingers 19-19 in accordance with the diameter of the binding element being spread.

A lever 85 is secured to the right hand outer end of the shaft 25 to effect adjustment of the arms 84-84 and the indexing roll 83. The lever 85 is abutted at its opposite sides by machine screws 86-86 threaded through angle brackets 87-87 secured to and extending outwardly from the right-hand side plate 26. Said machine screws serve to hold the lever 85 and the roller 83 in the desired position of adjustment.

The gap between the discharge end of the feeding plate 34 and the indexing roller 83 is closed by an inclined gap closing plate 91. Said gap closing plate has opposite depending sides 93-93 pivotally mounted on opposite reduced ends 94-94 of the indexing roller 83 on the insides of the links 84-84. As shown in Figure 4, when the indexing roller 83 is in its furthermost position from the backbone holding fingers 19-19, the upper end of the gap closing plate 91 is on a level with the top of the feeding plate 34 and is inclined downwardly to the periphery of the roller 83 at a relatively steep angle to support the binding element 15 to drop or roll downwardly onto the indexing roller 83 and to be rotatably supported thereby against the backbone holding fingers 19-19. The bottoms of the sides 93-93 of the gap closing plate 91 are slidably supported on support pins 95-95 projecting inwardly from the side walls 26-26 of the casing 11. A tension spring 96 is connected at one of its ends to a depending side 93 of the gap closing plate 91 and at its opposite end to the shaft 25 and serves to hold the sides 93-93 in engagement with the pins 95-95 in all positions of adjustment of the

indexing roller 83 with respect to the backbone holding fingers 19-19.

The pins 95-95 are so positioned with relation to the supporting surface of the gap closing plate 91 and its axis of pivotal connection to the indexing roller 83 and also with respect to the axis of pivotal movement of the links 84-84 that the gap between the discharge end of the feeding plate 34 or the forward end of the stop and drop bar 65 will always be closed to an extent sufficient to prevent a binding element 15 of the required size from dropping in the space therebetween in all positions of the indexing roller 83 with respect to the backbone holding fingers 19-19.

A motor 97, which may be a fractional horse power electric motor having a speed reducer incorporated therein, is herein shown as being provided to drive the indexing roller 83 by means of a yieldable belt 99 in the form of a closed tension spring having sufficient tension to rotatably drive the indexing roller 83 in all positions of adjustment thereof with respect to the motor 97.

It may be seen from the foregoing that as the stop and drop bar 65 is moved downwardly to a position so that its top is on a level with the top of the plate 34a, the binding element 15 may drop from the end of said plate along the more steeply inclined gap closing plate 91 into engagement with the indexing roller 83 and against the backbone holding fingers 19-19. The indexing roller 83 rotating at a relatively slow speed will then rotate the binding element 15 against the backbone holding fingers 19-19 into position for the rings of the binding element to pass between said fingers, regardless of the position or of the relation of the backbone of the binding element with respect to said backbone holding fingers, as it is discharged from the end of the plate 34. The binding element 15 is thus compelled by virtue of its rotatable movement imparted by the indexing roller 83 to change its position almost instantaneously as it comes into contact with said roller and to properly index itself with respect to the backbone holding fingers 19-19 with its rings between and beyond said backbone holding fingers and with its backbone in engagement therewith, ready for the spreading cycle.

It may be seen from Figure 2 that when plate 44 and the guide 53 are properly adjusted to the required width of the desired binding element to be spread and the stop and go and the stop and drop bars and the indexing roller 83 are properly set for the diameter of the binding element to be spread, that the hopper 34 may then be loaded with a plurality of binding elements, as shown. Upon depression of the lever 80, the stop and go bar 55 and the stop and drop bar 65 will both move downwardly with one binding element dwelling temporarily between the two bars, the stop and go bar preventing additional binding elements from sliding beyond it. At the end of downward travel of said bars, the binding element dwelling between the two bars will fall or slide down the gap closing plate 91 onto the rotatable indexing roller 83 against the backbone holding fingers 19-19 of the working head of the indexing machine. The hand may then be removed from the lever 80. The springs 70-70 and 71-71 will raise the stop and go and stop and drop bars to the positions shown in Figure 2, allowing another binding element to move downwardly along the feeding plate 34 and rest against the stop and drop bar 65. The binding

element resting on the rotating indexing roller 83 against the backbone holding fingers 19-19 will then be rotated into position for the rings thereof to extend between said fingers and said fingers coming into engagement with the inside of the backbone to hold the binding element in position for spreading. At this time the sector 24 and cam 23 may be turned in a clockwise direction by operation of the link 33. This will cause lateral movement of the backbone holding fingers 19-19 with respect to the plate 12 and will bring the insides of the rings 14-14 into position to be engaged by the laterally turned ends of the spreading fingers 20-20. Continued movement of said sector will move the spreading fingers 20-20 longitudinally along the plate 12 to uncurl or spread the rings with the upright inner ends 16-16 thereof extending upwardly from the plate 12 for the insertion of the sheets to be bound thereon.

Adjustable side guides for the binding elements may be removably mounted on the fingers 19-19 or may be adjustably mounted on the gap closing plate 91. As herein shown upright guides 101-101 are adjustably mounted on the plate 91 and extend upwardly and forwardly therefrom toward the fingers 19-19. Said guides are shown as having slotted bases 102-102 extending outwardly therefrom and held in position by wing nuts 103-103.

It will be understood that modifications and variations may be effected without departing from the scope and novel concepts of the present invention.

35 I claim as my invention:

1. In an indexing device adapted to position plastic binding elements having a backbone with spaced rings extending therefrom for opening and spreading of the rings and impaling of sheets thereon, holding means for the backbone of the binding element shaped to extend between the rings of the binding element and engage the backbone thereof, to hold the binding element during the spreading operation, and a binding element rotating means operatively associated with the holding means and adapted to support and rotate each individual binding element against said backbone holding means and to uniformly bring it into position to index itself with the rings thereof between and beyond the backbone holding means, ready for the spreading cycle.

2. In an indexing device adapted to position plastic binding elements having a backbone with spaced rings extending therefrom for opening and spreading of the rings and impaling of sheets thereon, holding means for the backbone of the binder shaped to extend between the rings of the binding element and engage the backbone thereof to hold the binding element during the spreading operation, an indexing roller at the receiving end of said backbone holding means adapted to support each individual binding element against the backbone holding means, and a motor connected to drive said roller and cause said roller to rotatably move each individual binding element into position to pass between said backbone holding means and cause the backbone thereof to come into engagement with said backbone holding means, with the rings thereof extending therebeyond.

3. In an indexing device adapted to position plastic binding elements having a backbone with spaced rings extending therefrom for opening and spreading of the rings and impaling of sheets

thereon, holding means for the backbone of the binding element shaped to extend between the rings of the binding element and engage the backbone thereof to hold the binding element during the spreading operation, an inclined feeding plate along which the binding elements are adapted to move into position to engage said backbone holding means, and a constantly rotating indexing roller interposed between the discharge end of said feeding plate and said backbone holding means to rotatably move each binding element against said backbone holding means and bring it into position for its backbone to come into engagement with said backbone holding means, with the rings thereof extending therebeyond.

4. In an indexing device adapted to position plastic binding elements having a backbone with spaced rings extending therefrom for opening and spreading of the rings and impaling of sheets thereon, holding means for the backbone of the binding element shaped to extend between the rings of the binding element and engage the backbone thereof to hold the binding element during the spreading operation, an inclined feeding plate adapted to support binding elements and having a discharge end, means for discharging the elements from the discharge end of said plate one at a time, an indexing roller interposed between the discharge end of said feeding plate and said backbone holding means and adapted to have the binding elements drop from said plate thereon, and means for driving said roller to rotatably move the binding element thereon against said backbone holding means and bring it into position for its backbone to come into engagement with said backbone holding means, with the rings thereof extending therebeyond.

5. In an indexing device adapted to position plastic binding elements having a backbone with spaced rings extending therefrom for opening and spreading of the rings and impaling of sheets thereon, holding means for the backbone of the binding element adapted to extend between the rings of the binding element and engage the backbone thereof to hold the binding element during the spreading operation, an inclined feeding plate having a discharge end, an indexing roller having its periphery disposed beneath the discharge end of said feeding plate and interposed between the discharge end thereof and said backbone holding means, means for discharging the elements from the discharge end of said plate one at a time onto said roller and against said backbone holding means, and means for driving said roller to rotatably move the binding element thereon against said backbone holding means and bring it into position for its backbone to come into engagement with said backbone holding means, with the rings thereof extending therebeyond.

6. In an indexing device adapted to position plastic binding elements having backbones with spaced rings extending therefrom for opening and spreading the rings and impaling of sheets thereon, holding means for the backbone of the binding element adapted to extend between the rings of the binding element and engage the backbone thereof, to hold the binding element during the spreading operation, an inclined feeding plate having a discharge end, an indexing roller interposed between the discharge end of said feeding plate and said backbone holding means, and having its periphery disposed beneath the discharge end of said plate, a support plate closing the gap between said feeding plate

and indexing roller, means for discharging the elements seriatim from the discharge end of said feeding plate along said support plate into said roller and against said backbone holding means, and a motor connected to rotatably drive said roller to rotatably move each binding element dropping thereon against said backbone holding means and bring it into position for its backbone to come into engagement with said backbone holding means, with the rings thereof extending therebeyond.

7. In an indexing device adapted to position plastic binding elements having backbones with spaced rings extending therefrom for opening and spreading of the rings and impaling of sheets thereon, holding means for the backbone of the binding element adapted to extend between the rings of the binding element and engage the backbone thereof to hold the binding elements during the spreading operation, an inclined feeding plate having a discharge end spaced from said backbone holding means, an indexing roller having its periphery disposed beneath said feeding plate and adjacent said backbone holding means, means for moving said roller toward or from said backbone holding means to adjust said roller for various sizes of binding elements, a gap closing plate between the discharge end of said feeding plate and the periphery of said roller, and a motor for driving said roller to rotatably move said binding element against said backbone holding means and bring it into position to come into engagement with said backbone holding means, with the rings thereof extending therebeyond.

8. In an indexing device adapted to position plastic binding elements having backbones with spaced rings extending therefrom for opening and spreading of the rings and impaling of sheets thereon, holding means for the backbone of the binding element adapted to extend between the rings of the binding element and engage the backbone thereof to hold the binding element during the spreading operation, an inclined feeding plate having a discharge end spaced from said backbone holding means, an indexing roller having its periphery disposed beneath said feeding plate and adjacent said backbone holding means, means for moving said roller toward or from said backbone holding means to adjust said roller for various sizes of binding elements, a gap closing plate interposed between the discharge end of said feeding plate and the periphery of said roller and mounted for movement with said roller upon adjustable movement thereof toward or from said backbone holding means, means slidably engaged by said gap closing plate and holding it in position, said means being so located with respect to said roller and feeding plate as to maintain the gap between the end of said feeding plate and said gap closing plate to cause the binding elements sufficiently close to drop on said gap closing plate into engagement with said roller in all positions of adjustment of said roller with respect to said backbone holding means.

9. In an indexing device adapted to position plastic binding elements having backbones with spaced rings extending therefrom for opening and spreading of the rings and impaling of sheets thereon, holding means for the backbone of the binding element adapted to extend between the rings of the binding element and engage the backbone thereof to hold the binding element during the spreading operation, an inclined feed-

11

ing plate along which the binding elements are adapted to move into engagement with said backbone holding means and having a discharge end spaced therefrom, an indexing roller disposed adjacent said backbone holding means and having its outer periphery disposed beneath the discharge end of said feeding plate, a transversely pivoted link having said roller mounted thereon, means for moving said link toward and from said backbone holding means to adjust the position of said roller with respect thereto to accommodate said roller to varying sizes of binding elements, and a motor connected to rotatably drive said indexing roller to rotatably move the binding element against said backbone holding means and bring it into position to come into engagement with said backbone holding means, with the rings thereof extending therebeyond.

10. In an indexing device adapted to position plastic binding elements having backbones with spaced rings extending therefrom for opening and spreading of the rings and impaling of sheets thereon, holding means for the backbone of the binding element adapted to extend between the rings of the binding element and engage the backbone thereof to hold the binder during the spreading operation, an inclined feeding plate along which the binding elements are adapted to move into engagement with said backbone holding means and having a discharge end spaced therefrom, an indexing roller disposed adjacent said backbone holding means and having its outer periphery disposed beneath the discharge end of said feeding plate, a transversely pivoted link forming an adjustable support for said roller, means for moving said link toward and from said backbone holding means to adjust the position of said roller with respect thereto, to accommodate said roller to varying sizes of binding elements, a gap closing plate pivotally connected to said link and closing the gap between the discharge end of said feeding plate and said indexing roller, means supporting said gap closing plate for slidable movement with said link and roller, said support means being so positioned with respect to said plate and said plate being so positioned with respect to said roller as to maintain the space between the discharge end of said feeding plate and the receiving end of said support plate sufficiently close as to prevent the smallest binding elements from dropping therethrough in all positions of said indexing roller with respect to said backbone holding means, and a motor connected to drive said indexing roller to rotatably move the binding element against the backbone holding means and bring it into position to come into engagement with said backbone holding means, with the rings of said binding element extending therebeyond.

11. In an indexing device adapted to position plastic binding elements having backbones with spaced rings extending therefrom for opening and spreading of the rings and impaling of sheets thereon, holding means for the backbone of the binding element adapted to extend between the rings of the binding element and engage the backbone thereof to hold the binder during the spreading operation, an inclined feeding plate along which the binding elements are adapted to move into engagement with said backbone holding means and having a discharge end spaced therefrom, an indexing roller disposed adjacent said backbone holding means and having its outer periphery disposed beneath the discharge end of said feeding plate, a motor, a drive con-

12

nnection from said motor to said indexing roller, a transversely pivoted link forming an adjustable support for said roller, means for moving said link toward and from said backbone holding means and for holding it in position to adjust the position of said roller with respect thereto to accommodate said roller to varying sizes of binding elements, a gap closing plate pivotally mounted on said link and closing the gap between the discharge end of said feeding plate and said indexing roller, means supporting said gap closing plate for slidable movement with said link and roller, and said support means being so positioned with respect to said plate and said plate being so positioned with respect to said roller as to maintain the space between the discharge end of said feeding plate and the receiving end of said support plate sufficiently close to prevent the smallest binding elements from dropping therethrough in all positions of said indexing roller with respect to said backbone holding means, and a spring maintaining said gap closing plate in slidable engagement with said support means.

25 12. In an indexing device adapted to position plastic binding elements having a backbone with spaced rings extending therefrom for opening and spreading of the rings and impaling of sheets thereon, holding means for the backbone of the binding element adapted to extend between the rings of the binding element and engage the backbone thereof, to hold the binding element during the spreading operation, an inclined feeding plate inclined downwardly toward said backbone holding feeding means and disposed in alignment therewith, an indexing roller interposed between the lower discharge end of said feeding plate and said backbone holding means and having its periphery disposed beneath the discharge end of said plate, a motor, a drive connection from said motor to said roller, means for discharging the binding elements from the feeding plate one by one onto said roller for indexing and spreading including two spaced vertically movable bars extending across said feeding plate and mounted for vertical movement with respect thereto, and means for moving said bars in synchronism and moving one bar into position to allow a binding element to drop from the end of said plate into said roller and the other bar into position to hold the other binding elements from movement along said feeding plate.

30 13. In an indexing device adapted to position plastic binding elements having backbones with spaced rings extending therefrom for opening and spreading of the rings and impaling of sheets thereon, holding means for the backbone of the binding element adapted to extend between the rings of the binding element and engage the backbone thereof to hold the binding element during the spreading operation, an inclined feeding plate inclined downwardly toward said backbone holding means and disposed in horizontal alignment therewith, an indexing roller interposed between the lower discharge end of said feeding plate and said backbone holding means and having its periphery disposed beneath the discharge end of said plate, a motor, a drive connection from said motor to said roller, and means for discharging the binding elements seriatim from the lower discharge end of the plate onto said roller for indexing and spreading, including two longitudinally spaced pivoted vertically movable bars extending transversely of said feeding

plate, one of said bars being disposed adjacent the discharge end of said feeding plate and being movable to allow a binding element to drop from the end thereof and the other of said bars being spaced rearwardly of said first bar and being movable toward said feeding plate as said first bar moves away from said plate, to hold the remaining binding elements on said plate from dropping beyond the end thereof, and means for moving said bars in unison toward and away from said plate.

14. A feeding device adapted to feed a plurality of plastic binding elements one at a time for spreading thereof and the impaling of the sheets to be bound thereon, a frame having an inclined feeding plate extending therealong, a binding element hopper on said plate and having guide means extending therefrom along said plate, serving to guide the binding elements as they move along, two longitudinally spaced bars pivotally mounted on said frame and extending transversely of said feeding plate, one being disposed adjacent the discharge end thereof and the other being spaced rearwardly therefrom, and means operatively connected with said bars to move said bars in unison and move said bar at the discharge end of said plate away therefrom to allow a binding element to move from the end thereof, and to move said other bar toward said plate to prevent more than one binding element from falling from the end of the plate.

15. A feeding device adapted to feed a plurality of binding elements one at a time for spreading thereof and the impaling of the sheets to be bound thereon, a frame having an inclined feeding plate extending therealong, a binding element hopper on said plate and having guide means extending therefrom along said plate, and serving to guide the binding elements as they move therealong, two longitudinally spaced bars extending transversely of said feeding plate, one being disposed adjacent the discharge end thereof and the other being spaced rearwardly therefrom, arms extending from said bars and pivotally mounting said bars on said frame for vertical movement toward and from said frame, a yieldable means interposed between said frame and bars and urging said bar at the discharge end of said plate in position to block the binding elements from discharging therefrom and urging said other bar in position to allow the binding elements to pass thereby, and other means operatively connected with said two bars to move the bar at the discharge end of said plate against said yieldable means in position to allow a binding element to drop therefrom and to move said other bar against said yieldable means into position to block the next succeeding binding element from dropping from the end of said plate.

16. An indexing device adapted to position plastic binding elements for opening and spreading thereof and impaling of sheets thereon including an inclined feeding plate having a discharge end, a plurality of backbone holding teeth spaced beneath and in advance thereof, and a rotatably driven roller interposed between the discharge end of said feeding plate and said holding teeth adjacent the lower ends thereof and adapted to have supporting engagement with the individual binding elements movable along said plate and to rotate each binding element against said fingers into position so that the rings of the binding element may pass therebetween with said teeth engaging the inside of the backbone thereof and the rings of the binding ele-

ment extending beyond said teeth ready for the spreading cycle.

17. In a binding machine adapted to spread rings of plastic binding elements having a curved backbone with spaced rings extending therefrom to permit sheets to be impaled thereon, said binding machine having a plurality of laterally spaced upright backbone holding teeth adapted to engage the backbone of the binding elements between the rings thereof and having a plurality of spreading fingers adapted to engage and spread the rings of the binding element for insertion of the book thereon, the improvement comprising an inclined feeding plate having a discharge end spaced from the receiving ends of said backbone holding teeth, and an indexing roller at the discharge end of said plate and in advance of said backbone holding teeth with its periphery adjacent the lower ends thereof and adapted to rotatably move the binding element along said teeth into position to pass therebetween with its backbone into engagement therewith.

18. In a binding machine adapted to spread rings of plastic binding elements having a backbone and spaced rings extending therefrom to permit sheets to be impaled thereon, said binding machine having a plurality of parallel spaced upright fingers adapted to extend between the rings of the binding element and engage the backbone thereof and also having a plurality of spreading fingers adapted to engage the insides of the rings of the binding element and to move in a longitudinal direction and uncurl or spread the rings for insertion of the sheets to be bound thereon, the improvement comprising an inclined feeding plate having a discharge end spaced in advance of the receiving ends of the backbone holding fingers of the binder and supporting the binding elements for downward movement therealong into registry with said backbone holding fingers, an indexing roller at the discharge end of said plate and at the receiving end of said backbone holding fingers, adjacent the lower ends of said fingers, and means for driving said indexing roller to position the binding element to pass between said backbone holding fingers and be held thereby with the backbone thereof in an upright position.

19. In a binding machine adapted to spread rings of plastic binding elements having a backbone and laterally spaced rings extending therefrom to permit sheets to be impaled thereon, said binding machine having a plurality of parallel spaced upright backbone holding fingers adapted to extend between the rings of the binder and engage the backbone thereof and also having a plurality of spreading fingers adapted to engage the insides of the rings of the binder and to move in a longitudinal direction and uncurl or spread said rings for insertion of the sheets to be bound thereon, the improvement comprising an inclined feeding plate having a discharge end in advance of said backbone holding fingers and supporting the binding elements for downward movement therealong into engagement with said fingers, an indexing roller spaced forwardly of and beneath the discharge end of said plate and having a rotating supporting surface adjacent the receiving ends of the backbone holding fingers of the binding machine and beneath the upper ends thereof and adapted to receive and rotate each binding element discharged thereon against said fingers into position for its rings to pass therebetween with the backbone thereof coming into engage-

ment with said fingers, a motor, and a drive connection from said motor to said indexing roller.

20. In a binding machine adapted to spread rings of plastic binding elements having a backbone and laterally spaced rings extending therefrom to permit sheets to be impaled thereon, said binding machine having a plurality of parallel spaced upright backbone holding fingers adapted to extend between the rings of the binding element and engage the backbone thereof and also having a plurality of spreading fingers adapted to engage the insides of the rings of the binding element and to move in a longitudinal direction and uncurl and spread the rings for insertion of the sheets to be bound thereon, the improvement comprising an inclined feeding plate having a discharge end spaced in advance of the receiving ends of said backbone holding fingers and supporting the binding elements for downward movement therealong into engagement with said holding fingers, an indexing roller spaced forwardly of and beneath the discharge end of said plate and adjacent the receiving end of said backbone holding fingers, and adapted to receive and rotate each binding element discharged thereon against said holding fingers into position to pass therebetween and engage the backbone thereof therewith, a motor, a drive connection from said motor to said indexing roller, means for adjustably moving said roller with respect to said holding fingers to accommodate various diameters of binding elements, and a gap closing plate interposed between the discharge end of said feeding plate and said indexing roller and connected with

said roller to move therewith upon adjustment thereof and so supported and guided as to maintain the gap between the end of said feeding plate and said gap closing plate smaller than the diameter of the smallest binding element spread, in all positions of said indexing roller with respect to said feeding plate.

21. In a binding machine for use with binding elements having backbones with spaced-sheet-receiving rings extending therefrom, means for positioning and holding a binding element for spreading of the rings and impaling of sheets thereon, the positioning and holding means comprising a plurality of fingers constructed and arranged to extend between the rings and against the backbone of the binding element, means for guiding the binding element into engagement with the fingers, and means operatively associated with the fingers and arranged to frictionally engage and rotate the binding elements to a position in which the fingers extend between the ring portions thereof and abut the backbone thereof.
